R. J. TRAVERS,
ELECTRIC LAMP STAND,
FILED MAY 13, 1921.

FIG. 2

INVENTOR.

ROLAND J. TRAVERS
BY *A. B. Bowman*
ATTORNEY

UNITED STATES PATENT OFFICE.

ROLAND J. TRAVERS, OF SAN DIEGO, CALIFORNIA.

ELECTRIC-LAMP STAND.

Application filed May 13, 1921. Serial No. 469,284.

To all whom it may concern:

Be it known that ROLAND J. TRAVERS, a citizen of the United States, residing at San Diego, in the county of San Diego and 5 State of California, has invented a certain new and useful Electric-Lamp Stand, of which the following is a specification.

My invention relates to electric lamp stands more particularly a stand for supporting an incandescent light bulb and 10 socket, for residence and business use, and the objects of my invention are: first, to provide an insulated lamp stand of this class, which is made up largely of telephone 15 parts, so that the parts may be purchased and assembled with but slight changes; second, to provide a lamp stand of this class, which is composed of insulated material throughout particularly the part that a person 20 grasps when moving it about; third, to provide a lamp stand of this class, with a heavy base, so that it will not readily tip over and break; fourth, to provide a lamp stand of this class which consists principally 25 of a telephone transmitter base, receiver and mouthpiece, and fifth, to provide a lamp stand of this class which is very simple and economical to construct easy to connect to the lamp socket, durable, insulated and 30 which will not readily deteriorate or get out of order.

With these and other objects in view as will appear hereinafter, my invention consists of novel features of construction, combination, and arrangement of parts and portions 35 as will be hereinafter described in detail and particularly set forth in the appended claims, reference being had to the accompanying drawings, and to the characters of reference thereon which form a 40 part of this application, in which:—

Figure 1, is a longitudinal, sectional view of the stand complete, showing the socket and lamp and a portion of its connecting 45 pipe in elevation to facilitate the illustration, and Fig. 2, is a transverse sectional view through 2—2 of Fig. 1.

Similar characters of reference refer to similar parts and portions throughout the 50 several views of the drawings.

The base 1, pad 2, sleeve 3, nuts 4 and 5, separator 6, washer 7, nut 8, pipe 9, receiver head member 10, receiver member 11, and transmitter mouthpiece 12 constitute the 55 principal parts and portions of my electric lamp stand.

The base consisting of the members 1 and 2, is an ordinary telephone transmitter support base piece, the portion 1 being metallic or hard rubber insulation and the part 2 60 is a cushion secured to the bottom thereof so that it will not scratch objects upon which it is placed and forming a base for supporting the stand. The conventional telephone transmitter support is provided internally 65 with a pipe 3, which extends upwardly for supporting the telephone mouth piece. In my construction, this is cut off forming the sleeve 3, secured to the base by means of the nut 5 on the underside which is a conventional nut for supporting this pipe 3 in 70 position on the base. The receiver head member 10 is placed over the pipe 3 and secured thereto by nut 4, which is also a conventional nut for supporting this pipe 3 75 and receiver head member on the base. In this receiver head member 10, is screwed the receiver member 11, which is a conventional telephone receiver casing except that at the small end, the hole through which the cord 80 usually passes is enlarged slightly and adapted to fit around a quarter inch pipe, the preferable size for the pipe 9, and the mouthpiece of the transmitter is positioned on the upper end of this receiver member with 85 its small end down and its other end is adapted to receive the end of the socket which supports the lamp. This socket is screwed onto the upper end of the pipe 9 the pipe 9 being of the proper size to receive threads in the socket. Positioned in 90 the lower end of the pipe member 3 is a separator 6 which is preferably of insulating material. Positioned against the end of the pipe 3 and the separator 6 is a washer 7 95 which is preferably an insulated washer and against this washer on the end of the pipe 9 which is threaded is the nut 8 which is adapted to screw thereon and secure the pipe 9 rigidly in position drawing the lamp 100 socket down into the large open end of the mouth piece 12 rigidly securing it in position as shown best in Fig. 1 of the drawings. This pipe 9 forms a conduit for the electric circuit wires which connect the 105 socket with any source of electrical energy for producing the light.

Though I have shown and described a particular construction, combination and arrangement of parts and portions I do not 110 wish to be limited to this particular construction, combination and arrangement but

desire to include in the purview of my invention the construction, combination and arrangement substantially as set forth in the appended claims.

5 It is obvious that with this construction there is provided a lamp stand which is made up almost entirely of telephone parts which may be readily constructed by purchasing the parts in different localities and 10 assembling them close to the place of distribution. That the assembling of the parts is only a small undertaking. With the proper facilities a lamp stand of this class could be made in different localities without 15 any machinery for making the parts because most of the parts are already manufactured for other purposes. That the device is simple, economical of construction, durable, and a finished mechanical product.

20 Having thus described my invention what I claim as new and desire to secure by Letters Patent is:

1. An electric lamp stand including, a conventional telephone transmitter support 25 base member, a telephone receiver member with its large end down positioned on said base member a sleeve and nut means extending into said receiver member and said base member separately securing said members 30 together; a telephone mouth piece loosely positioned on the upper end of said telephone receiver member, a pipe member extending through said receiver member adapted to connect with an electric light bulb 35 socket at its upper end positioning said mouth piece relatively to said receiver member and its other end supported in said base.

2. An electric lamp stand including, a conventional telephone transmitter support base 40 member, a telephone receiver member with its large end down positioned on said base

member a sleeve and nut means extending into said receiver member and said base member separately securing said members together; a telephone mouth piece loosely positioned on the upper end of said telephone receiver member, a pipe member extending through said receiver member adapted to connect with an electric light bulb socket at its upper end positioning said mouth piece 45 relatively to said receiver member and its other end supported in said base and means adapted to be screwed on the lower end of said pipe adapted to draw the lamp socket member against said mouth piece for securing all of said members in certain relative 50 positions to each other, and an electrical conductor connecting with said socket passing through said pipe and out through the hole in said telephone base member.

3. An electric lamp stand including, a base member provided with a hole in its upper side, a handle member positioned over the hole in said base member and extending above the same, a hollow externally threaded 55 sleeve extending through said members positioning the same relatively to each other, nuts on said sleeve engaging the lower portion of said handle member and said base member securing said handle and base members 60 to each other, a pipe threaded at opposite ends extending through said sleeve and said handle member, an electric light bulb socket secured on the upper end of said pipe and a nut on the lower end thereof 65 adapted to engage said sleeve for securing said members in certain relation and alignment with each other.

In testimony whereof, I have hereunto set my hand at San Diego, California, this 80 2nd day of May, 1921.

ROLAND J. TRAVERS.
